UNITED STATES PATENT OFFICE.

HENRY W. SPOONER, OF BROOKLYN, NEW YORK.

DAM.

Application filed June 18, 1925. Serial No. 37,884.

In the design of concrete or masonry dams for the impounding of water it is not always possible to compute the various opposing forces with as great a degree of accuracy as 5 is desirable. These forces are all governed by the general laws of gravitation, yet one of the most important factors, namely the uplift against the bottom of the dam, is usually indeterminate. This leads to a certain 10 amount of guesswork in the design, which in many cases is incorrect, as has been proved by the all too frequent instances of dam failures, which in many cases have resulted in great loss of life and property.

15 The failure of a concrete or masonry dam is always due to one or more of three causes: These are overturning, sliding down stream, or fracturing under the pressure exerted by the impounded water. The total water pressure 20 acting against the face of the dam may be determined very closely. The opposing force of gravitation due to the weight of the structure itself may be computed with a reasonable degree of accuracy, and to this 25 may be added a part of the inertia of the foundation by imbedding the dam into the rock. Sliding down stream can thus be prevented, but it involves considerable expense due to the additional rock excavation and 30 masonry required.

The danger of overturning or fracturing 35 may be eliminated by building the dam sufficiently heavy to overcome both the horizontal and vertical components of the water pressure, but this procedure also involves considerable extra expense. The total cost 40 of a dam is an important consideration, and for this reason the temptation exists to reduce the factor of safety against failure to 45 a ratio far smaller than is ordinarily used in other branches of engineering design. The theoretical factor of safety may in practice be still further reduced and may even become negative if insufficient allowance for uplift has been made in the calculations.

Uplift is that force which operates against 50 the bottom of the dam in a vertical direction, and is caused by seepage of water underneath the dam under the full hydrostatic head on the upstream side, or by springs 55 arising through fissures in the foundation, or by both of these causes combined. The total force of uplift is the sum of the products of the various hydrostatic pressures 60 to the various areas which are not in perfect and complete contact with the foundation.

It is obvious that these forces and their centers of pressure are not only indeterminate, but also that they may vary in intensity and location over the entire base of the dam. 60

Uplift against the base of a dam tends not only to overturn it, but also to cause fracture at or near the toe, or downstream edge. It may also increase the tendency to slide downstream by reducing the friction between the base of the dam and its foundation. 65

Heretofore, the tendency for dams to overturn and the force of uplift has been counteracted solely by the force of gravity in the 70 mass of the dam itself.

I aim to provide a dam of improved design and construction in which the tendency of uplift is reduced or entirely eliminated by the provision of means for introducing an 75 additional force to counteract the horizontal component of the water pressure on the upstream side of the dam. I thus increase in any given dam section the factor of safety 80 against overturning, fracturing, or sliding down stream.

The invention, which is pointed out with particularity in the appended claims, will be apparent from the following specification when read in connection with the accompanying drawings in which— 85

Fig. 1 is cross-sectional view of a dam embodying my invention;

Fig. 2 is a fragmentary longitudinal section on line 2—2 of Fig. 1; 90

Fig. 3 is a fragmentary view illustrating a modification.

Referring in detail to the embodiments of the invention illustrated—

Figure 1 represents a typical cross section of a gravity dam of concrete construction founded in rock, part of whose length is of the bulkhead type as indicated by *a*; the balance of its length having an overflow or spillway section *b*. An inspection tunnel or gallery *c* extends throughout the length of the dam, such as is ordinarily provided in dams of fair size or importance. A drainage trench *d* extends lengthwise under the dam at the downstream edge of the cut-off trench and wall *e*. A plurality of open grooves *f* extend at right angles to and connect with drainage trench *d* and form shallow chambers between the dam and its foundation. The total area of such chambers in a given design is dependent on the safe allowable unit pressure on the remaining 95 100 105 110

area of the base, or in other words, on that portion of the dam in actual contact with its foundation.

The longitudinal section, Fig. 2, shows the several grooves *f* connecting into trench *d*, A pipe *g* extends through the concrete between the inspection tunnel *c* and the drainage trench *d*, its open end terminating near the bottom of the latter. Located in inspection tunnel *c* or in an enlarged chamber of the same is a combined water ejector and air pump *h* having a water supply pipe *j* connecting its inlet with a screen chamber *k* located near the top of the dam on its upstream side. A discharge pipe *l* extends from the outlet nozzle of *h* through the lower portion of the dam and terminates on the downstream side, preferably at or near the toe of the spillway section. A valve *h'* is provided to prevent flow of water through the pipe *j* when the pump is disconnected for making repairs.

The screen chamber or inlet *k* is located at a predetermined elevation such that when the head water level does not exceed that elevation, the dam will have an ample factor of safety to resist through its own weight the combined horizontal and vertical components of the hydrostatic pressure. The elevation of inlet *k* is such that with an increase in the head water level above that point the wasting of a comparatively small amount of water is not objectionable.

As the pipes *g* and *l* and the interconnecting pump or ejector *h* offer a free passage between the trench *d* and the downstream exterior of the dam, any water collecting in trench *d* or the interconnecting grooves *f* will flow out through these pipes, up to the limit of their capacity under the hydrostatic head existing in trench *d*. Therefore the hydrostatic head or uplift under the base of the dam will be measured by the difference in elevation between the grooves *f* and the highest point of pipe *l*, unless the flow of water from trench *d* through pipes *g* and *l* is sufficient to cause an additional friction head. It is therefore obvious that the combination of the grooves *f* and their communicating trench *d* together with the pipes *g* and *l* provide a means of limiting the hydrostatic pressure under the base of the dam.

When the head water level reaches or exceeds the elevation of inlet *k*, water flows down the supply pipe *j* and through the ejector or air pump *h*, discharging downstream through pipe *l* and inducing a partial vacuum in suction pipe *g*. This causes any water collected in trench *d* and its intercommunicating grooves *f* to flow upward through pipe *g* and to be discharged through pipe *l*, due to the atmospheric pressure in the drainage trench *d*.

The action of air pump *h* resulting from the flow of water through supply pipe *j* is

first to remove the water from trench *d* and intercommunicating spaces *f*, and then to create a partial vacuum by removing most of the air from these spaces. This results in superimposing on the crest and downstream face of the dam an atmospheric load which is equal to the product of the negative pressure under the dam times the combined areas to the open spaces between the dam and its foundation.

The action of the pump first relieves the dam from any uplift pressure due to the hydrostatic head on the water collected under the dam, following which it builds up a partial vacuum below the dam and thus superimposes a corresponding atmospheric load on the outside of the dam. This atmospheric load opposes the horizontal component of the water pressure by increasing the effective weight of the dam, thereby tending to eliminate all three causes of failure, namely, overturning, fracturing, and sliding downstream.

The atmospheric pressure acting on the crest and exterior surface of the dam increases its effective weight and correspondingly increases its strength throughout its height, tending thereby to reduce the likelihood of fracture at any point, or the danger of overthrowing any part of the dam above any given horizontal construction joint. Furthermore, the increase in weight has the effect of moving the position of the resultant toward the upstream edge of the base, thereby reducing the pressure between the toe of the dam and its foundation and correspondingly decreasing the likelihood of fracture at that point.

It is of course desirable that the lower section of the dam, just above the open spaces *d* and *f*, be made practically air tight, and such construction is entirely feasible. A substantially or approximately air tight structure and an efficient air pump can be depended upon to produce a degree of vacuum sufficient to satisfy all practical requirements.

While I have shown and described a single pump, it will be understood any desired number may be used depending on the governing conditions. Neither are the pump inlet chambers required to be placed at the same elevation; they may be located at various levels so as to operate in sequence and reduce the force of uplift inversely with an increase in head, combining to create a vacuum after the water level has reached the uppermost inlet and sealed the air vents formed by unsubmerged inlet pipes.

Although I prefer to neutralize the uplift pressure by creating a vacuum under the dam by means of an ejector type of pump, the same result may be accomplished by means of a mechanical pump of either the rotary or reciprocating types, or in fact with

any pump which will handle water, and air below atmospheric pressure.

While the foregoing disclosure sets forth an efficient means for accomplishing the desired results, a less costly alternative construction but also a less efficient means could be employed as shown in Fig. 3 by connecting the trench *d* by means of a pipe *t*¹ or duct extending through the dam to the downstream toe and terminating in a nozzle *t*² of suitable construction pointing in the direction of flow of water passing over the spillway. Overflowing water submerging this nozzle and passing it at sufficient velocity would serve the same purpose as the pump *h* above described, though less effectively.

The chambers *f* and trench *d* between the dam and its foundation may be constructed in any suitable manner, such as by using light metal forms, or light arches of tile or pre-cast concrete or the equivalent placed on the foundation before pouring the lower course.

While the drawing shows the drainage trench *d* in a position parallel to the axis of the dam, with the interconnecting openings *f* at right angles to it, I am not limited to this arrangement. Any desired arrangement of these openings may be adopted to conform to the character of the foundation and other controlling conditions peculiar to the location of the dam, and if preferred the drainage trench *d* may be placed near the center of the dam or at the downstream end.

Various modifications may be made by those skilled in the art without departing from the invention as defined in the appended claims.

What I claim is:

1. The combination with a dam and its foundation of means for creating a partial

vacuum between said dam and foundation.

2. A dam having chambers formed in the base portion thereof and means for creating a differential pressure between said chambers and the exterior of the dam whereby an atmospheric load is superimposed on the dam.

3. A dam formed with chambers between its base and its foundation and means for utilizing the water impounded by the dam for creating a partial vacuum in said chambers.

4. A dam having chambers between its base and its foundation and means whereby the factor of safety against failure of the dam is increased with a rise in the head water level by utilizing part of the impounded water to create a partial vacuum in said chambers.

5. A dam having at least one substantially air tight chamber between its base and its foundation and a means responsive to changes in the level of the impounded water for creating a partial vacuum in said chamber.

6. A dam having chambers under the base thereof, a pump arranged to be actuated when the water impounded by the dam reaches a predetermined level, a suction duct connecting the pump with said chambers, and an outlet duct from the pump extending to the downstream side of the dam.

7. In combination with a dam structure having chambers under its base, a pump operated by the flow of water, a water inlet connected to said pump from the upstream side of the dam, a suction line connecting said pump with said chambers and a discharge duct leading from the pump to the downstream side of the dam.

In witness whereof, I have hereunto signed my name.

HENRY W. SPOONER.
